[57] CLAIM

The ornamental design for a console for enzyme immunoassay auto analyzer, as shown and described.

DESCRIPTION

FIG. 1 is a front elevational view of a console for enzyme immunoassay auto analyzer showing my new design;

FIG. 2 is a rear elevational view thereof;

FIG. 3 is a top plan view thereof;

FIG. 4 is a right side elevational view thereof; and,

FIG. 5 is a left side elevational view thereof.

The bottom plan view of the claimed design is plain and unornamented.
